PISTON

John N. Martin, Tulsa, Okla.

Application August 12, 1937, Serial No. 158,766

8 Claims. (Cl. 309—4)

This invention relates to pump plungers or pistons and particularly to composition packed plungers.

An object of this invention is to provide a plunger adapted to move against high fluid pressures.

Another object is to provide a plunger which is packed with a series of spaced composition packing rings, each of which is individually supported on the plunger body without the use of removable spacers or compression nuts.

A specific object is to provide a plunger upon which the packing is spirally arranged, and substantially fluid-tight.

Other objects and advantages of this invention will be apparent from the following detailed description in conjunction with the accompanying drawing which illustrates one form of the new invention.

20 In the drawing:

Figure 1 is an elevation of the plunger of this invention showing the packing in place.

Figure 2 is a transverse section taken along line 2—2 of Figure 1.

25 Figure 3 is a vertical section taken along line 3—3 of Figure 1.

Figure 4 is an elevation of the plunger body with the packing removed.

Figure 5 is a transverse section taken along line 5—5 of Figure 4.

30 Figure 6 is a fragmentary view of a plunger in accordance with this invention showing another arrangement of packing thereon.

Referring to the drawing, the plunger of this invention comprises a cylindrical body 10 of any suitable metal, having an axial bore 11 for the passages of fluid therethrough as in the case of the conventional oil well pump. Body 10 is reduced in section at each end, the reduced section being threaded externally, as indicated at 12, for attachment to necessary valves and other pumping equipment. It will be understood that in some cases the reduced ends may be threaded internally or one end may be threaded internally and the other externally, depending upon the type connection to which the plunger is to be attached. A continuous helical groove 13 is cut into the outside of body 10, the groove being generally square in cross-section. The convolutions of the groove are spaced apart, the metal not removed in the grooving operation forming a continuous helical spacer 14. A continuous coil of composition packing 15 is mounted in groove 14.

35 55 Packing 15 is preferably of such size and shape

as to substantially fill groove 13 and to extend radially beyond the edges of spacer 14, in order to fit closely within a conventional pump cylinder (not shown) which ordinarily has an internal diameter slightly larger than the external diameter of the plunger body 10. With packing 15 arranged in grooves 13 as above described, a continuous helical channel will be formed between the edges of the convolutions of the packing, the bottom of the channel being the outer face of 10 spacer 14. To prevent the fluid being pumped from flowing along this channel, notches 16 are cut into spacer 14 and into these notches are inserted packing segments 17. These segments are cut to fit tightly in notches 16 and to extend 15 radially from body 10 the same distance as packing 15, thus making the outer faces of these packing segments flush with the outer or cylinder contacting face, of the main packing 15.

As shown in Figure 4, notches 16 may be cut in 20 each of the convolutions of spacer 14 and these notches may all be in alignment, rows of such notches being provided on opposite sides of plunger body 10. Figure 6 illustrates an arrangement of packing, in which notches 16 are at different points along spacer 14 and the corresponding packing segments 17 form a "staggered" pattern between the convolutions of packing 15.

By described arrangement of packing segments 17, a series of dams are formed between the convolutions of packing 15, thus effectively sealing 30 the channels between these convolutions and preventing the leakage of fluid past the plunger when same is in operation.

35 Groove 13 is preferably rectangular in cross-section generally approaching a square, and the packing 15 has a corresponding cross-section, although its thickness, in radial direction with respect to body 10 is greater than the depth of groove 13, thus permitting the packing to protrude beyond the mouth of groove 13 and beyond the outer face of spacer 14. Spacer 14 is also rectangular in cross-section but is generally narrower than groove 13. For example, groove 13 may be one-quarter inch wide by seven-sixteenths 40 inch deep and packing 15 one-quarter inch square, thus the packing will protrude one-sixteenth inch outside groove 13. Spacer 14 will be seven-sixteenth inches deep by one-eighth inch wide. Notches 16 will extend entirely through 45 spacer 14 and be of any suitable depth, preferably the same as that of groove 13 and any length, for example one-quarter inch or more as desired.

45 50 In my application Serial No. 140,703, filed May 4, 1937, I have described a packing arrangement 55

for pump plungers wherein composition packing is used, which has the characteristic of swelling when immersed in the fluid being pumped, and by such swelling, the packing becomes firmly embedded in the grooves and protrudes therefrom sufficient to form a close pumping fit in the pump cylinder. In the present invention, I may utilize packing of similar character, in order that the packing may wedge itself sufficiently tightly into groove 13 to prevent leakage of fluid between the sides of the groove and packing 15. Packing segments 17 may be of similar material for the same purpose.

As in my former application, in this invention each convolution of packing 15 is independently supported by the segment of groove 13 in which it is placed. Thus no tightening nuts are required to hold the packing in place and each convolution of packing will support a proportional part of the pumping load. The distortion or wearing out of any convolution of packing 15 will, therefore, have no appreciable detrimental effect on the remainder of the packing other than to transfer its portion of the total load to the remaining portions of the packing.

The spacer 13 may be formed, as described, by grooving the outer surface of the piston body, or it may be formed by slipping a metal spiral of the proper shape over a smooth cylindrical body and welding or shrinking, the convolutions thereof on the body to form a rigid bond with the body.

Various types of packing may be used. As noted above, packing having predetermined swelling characteristics may be used, or fixed dimension packing may be used and may be pressed into the groove 13 to provide a tight fit therein, and the same applies to packing segments 17.

Various changes and modifications may be made in the size, shape and form of the elements comprising this invention without departing from the scope of the appended claims.

What I claim and desire to secure by Letters Patent is:

1. A helically packed piston of the class described comprising, a cylindrical piston body, a helical packing seat on said body, a continuous helical packing element mounted in said seat in fluid-tight engagement therein throughout its length, and discontinuous packing elements mounted between adjacent convolutions of said continuous packing element and adapted to form a fluid tight seal therebetween, said discontinuous packing elements protruding radially to the outer periphery of said continuous packing element.

2. A helically packed piston of the class described comprising, a cylindrical piston body, a helical packing seat on said body, a continuous helical packing element constructed of composition material mounted in said seat in fluid-tight engagement therein throughout its length, and discontinuous packing elements constructed of composition material mounted between adjacent convolutions of said continuous packing element and adapted to form a fluid tight seal therebetween, said discontinuous packing elements protruding radially to the outer periphery of said continuous packing element.

3. A piston comprising a cylindrical body, a packing seat rigidly united with said body and helically arranged thereon in a plurality of spaced convolutions, a continuous composition

packing element mounted in said seat in fluid-tight engagement therein throughout its length and discontinuous composition packing elements mounted in the spaces between adjacent said convolutions and adapted to form a fluid-tight seal therebetween, said discontinuous packing elements protruding radially to the outer periphery of said continuous packing element.

4. A piston comprising a cylindrical body, a helical groove extending about a portion of said body, the convolutions of said groove being spaced apart to provide a helical spacer therebetween, spaced notches in said spacer between adjacent said convolutions, a continuous composition packing element mounted in said groove in fluid-tight engagement therein throughout its length, and segmental composition packing elements mounted in said notches and adapted to form a fluid-tight seal between adjacent convolutions of said continuous packing element, said segmental packing elements protruding radially to the outer periphery of said continuous packing element.

5. A piston comprising a cylindrical body, a helical groove extending about said body, a continuous composition packing element mounted in said groove in fluid-tight engagement therein throughout its length, and discontinuous composition packing elements mounted between adjacent convolutions of said continuous packing element, and adapted to form a fluid-tight seal therebetween, said discontinuous packing elements protruding radially to the outer periphery of said continuous packing element.

6. A piston comprising a cylindrical body, a helical member rigidly united with the outer surface of said body and extending laterally therefrom, the convolutions of said member being spaced apart forming a helical groove about said body, a continuous packing element mounted in said groove in fluid-tight engagement therein throughout its length and protruding radially thereof, and discontinuous packing elements mounted between adjacent convolutions of said packing element and in fluid-tight engagement therewith, said discontinuous packing elements protruding radially to the outer periphery of said continuous packing element.

7. A piston comprising a cylindrical body, a helical groove extending about a portion of said body, a continuous packing element mounted in said groove in fluid-tight engagement therein throughout its entire length, and discontinuous packing elements mounted between adjacent convolutions of said continuous packing element and in fluid-tight engagement therewith, said discontinuous packing elements protruding radially to the outer periphery of said continuous packing element.

8. A piston comprising a cylindrical body, a helical groove extending about a portion of said body, the convolutions of said groove being spaced apart to provide a helical spacer therebetween, spaced notches in said spacer, a continuous packing element mounted in said groove in fluid-tight engagement therein throughout its length, and segmental packing elements mounted in said notches and in fluid-tight engagement with adjacent convolutions of said continuous packing element, said segmental packing elements protruding radially to the outer periphery of said continuous packing element.

JOHN N. MARTIN.
